Primary Examiner — John Windmuller*Assistant Examiner* — Steven Czyz(74) *Attorney, Agent, or Firm* — Timothy J. Monahan;
Monahan & Company, LLC(57) **CLAIM**

The ornamental design for an ergonomic thimble, as shown and described.

DESCRIPTION

FIG. 1 is a right side view of an ergonomic thimble.
FIG. 2 is a view of the underside of the ergonomic thimble.
FIG. 3 is a view of the top of the ergonomic thimble.
FIG. 4 is a view of the top and right side of the ergonomic thimble.

FIG. 5 is a view of the underside and left side of the ergonomic thimble; and,

FIG. 6 is a view of the back and right side of the ergonomic thimble.

The text "Prym" forming part of the claimed design is a registered trademark of Prym Consumer USA, Inc.
